UNITED STATES PATENT OFFICE.

FREDERICK H. LIEKER, OF TORONTO, ONTARIO, CANADA.

PURSE.

SPECIFICATION forming part of Letters Patent No. 364,529, dated June 7, 1887.

Application filed April 8, 1887. Serial No. 234,139. (No model.)

To all whom it may concern:

Be it known that I, FREDERICK HENRY LIEKER, of the city of Toronto, in the county of York, in the Province of Ontario, Canada, 5 manufacturer, have invented certain new and useful Improvements in Purses, of which the following is a specification.

The object of the invention is to devise a purse having the material which forms the 10 body of the purse-pocket on which the inner frame rests so cut at the upper corners as to form a strong bearing for the ends of said inner frame, and at the same time form strong double folds on which the gusset material forming the ends of the purse-pockets is pasted. 15 By my method of leaving the ends of the material from which the pockets are made square, or nearly so, and cutting out small wedge-shaped pieces from the upper corners 20 of the portion which carries the inside metal frame, (instead of making the purse-pockets in the usual manner,) I am able to dispense with four gusset-folds on the ends of the purse-pockets, as hereinafter explained, thereby 25 saving much labor and waste of material, besides making a stronger, more durable, and readily-made purse.

In the class of purses to which my invention is applicable the gusset-pieces forming the ends 30 of the pockets are pasted over the pocket material.

Figure 1 is an oblong piece of paper or other material from which the pockets in my purse are formed, the heavy dotted lines showing 35 the wedge-shaped portions cut out and wasted. Fig. 2 is an end view of the pocket material in my purse with gusset material removed, indicating the mode of folding the oblong piece of material shown in Fig. 1. Fig. 3 is a view 40 illustrating the wedge-shaped pieces cut out of the upper corners of the central folds in my purse. Fig. 4 is a perspective view of the frame-work of my improved purse-pockets, showing one end before being covered with the 45 gusset material, while the other end is covered with such gusset material and shows the number of folds in the gusset-piece in my style of purse-pockets.

Like letters indicate similar parts in the 50 different figures, all of which are intended to

represent parts of a purse having five pockets in process of formation.

In Fig. 1 the heavy lines *j k l m*, between folds 2 and 3 and 8 and 9, show where the material is cut into along the fold-line for about three-fourths of an inch, in order to afford expansion-pieces for the two pockets on either side of the central pocket. The wedge-shaped pieces, like *a b c d*, are cut or stamped out at the corners of the folds 4 5 and 6 7, as shown, 60 the inner metal frame, *F*, resting and being pinched onto the edge of folds indicated by dotted lines *e f* and *g h*, when the material is folded and shaped into position. *i*, being that portion between the double dotted lines between folds 5 and 6, forms the bottom of the central pocket, which carries the inner metal frame when my purse is formed. The piece of material as shaped in this figure is intended 65 to form a purse having five pockets. 70

In Fig. 2, for the purpose of illustrating the zigzag method of folding the oblong piece of material referred to in Fig. 1, the bottoms of the folds are not yet gathered together, and the slits between folds 2 3 and 8 9, forming expansion-pieces for the ends of pockets in which the gusset-leather is pasted, are also shown in position, as well as the wedge-shaped pieces *a b c d* at the upper corners of the central pocket which carries the inner metal frame. 75 80

Fig. 3 shows a portion of the frame material which forms the purse-pockets in which the central frame rests, *i* being the bottom of the central pocket, and *G G* and *H H* being the double flaps or folds, which when the pockets 85 are expanded are folded back together outwardly from the central pocket, forming triangular-shaped expansion-pieces at both ends for the pockets adjoining the central pocket, and which are covered by the gusset-leather 90 forming the ends of the pocket, the pieces *G G* and *H H* being respectively held together by the gusset-leather and forming a strong support therefor.

In Fig. 4 the various letters and figures sufficiently indicate the position of the different parts and folds. It will be noticed at the end which is not covered with the gusset-leather that the double expansion-folds *G G* and *H H*, when the pockets are expanded, are folded out. 95 100

wardly from the central pocket to meet the edges of the flaps L L', formed by the slits at *j* and *l*, the other flaps formed at *j* and *l* being bent outwardly to meet the edges of folds 1 and 10, as shown. The outer edges may be glued together, if desired, before pasting on the gusset-piece covering the ends of the pockets. The other end shows the gusset-piece I pasted in position. The dotted lines show the position of the metal frame, the edges of said gusset-piece at the central pocket being tucked in and covered by said metal frame F when the purse is completed. It will be also noticed that in my way of making these purse-pockets there are only three inward folds of the gusset-piece in making a purse of five pockets, instead of five inward folds in the formation of a similar purse by any other known method where the gusset is pasted over the edges of the pocket-folds, and I thus effect a saving of four inward folds—two at each end. The same saving would of course be effected even if there were a larger or lesser number of pockets than five.

25 In my method a large number of wedge-shaped pieces can be cut out at a time without any cutting and gluing together again. It is not absolutely essential, but preferable, to have the pocket which carries the inner metal frame placed in the center of the purse. Having shown that four inward folds of gusset-leather forming the ends of pockets are saved in each purse made by my method, and that in my purse the wedge-shaped pieces can be cut out of the material forming the frame-work of the pockets in a number at a time rapidly and with comparatively little labor, and that the gusset-piece in my method does not require as much preparation by shaping the ends on which the frame is pinched, what I claim as my invention is—

1. In a purse where the gussets are pasted over the ends of the pocket material, notches *a b c d*, formed at the upper corners of the material forming the frame-work of pockets, the

double expansion-folds G, and the flap or fold L, in combination with the gusset-piece I, substantially as and for the purpose specified.

2. In a purse where the gussets are pasted over the ends of the pocket material, notches *a b c d*, the double expansion-folds G and H, and the flaps or folds L L', formed at the ends of the pockets adjoining the pocket which carries the inner metal frame, in combination with the gusset-piece I and the inner metal frame, F, substantially as and for the purpose specified. 50

3. In a purse where the gussets are pasted over the ends of the pocket material, the notches *a b c d*, formed on the folds which carry the inner metal frame, and the double expansion-folds G and H, in combination with the gusset-piece I and the material forming the ends of the pockets adjoining the pocket which carries the metal frame F, substantially as specified. 60

4. In a purse where the gussets are pasted over the ends of the pocket material, the gusset-piece forming the ends of the pockets so adapted to the frame of the purse as to form at the ends of the pocket which carries the inner metal frame a single inward fold which starts from the outermost edges of the pockets adjoining the pocket carrying the said inner metal frame, substantially as specified. 70

5. In a purse where the gussets are pasted over the ends of the pocket material, the folds which are notched at the upper corners and which carry the inner metal frame, forming at the ends thereof flaps of a double thickness of material, which fold outwardly from the pocket which carries the metal frame in a triangular form when the pockets of which said triangularly-shaped flaps form part are expanded, substantially as specified. 75

Toronto, March 31, 1887.

FREDERICK H. LIEKER.

In presence of—

JOHN G. RIDOUT,
CHARLES C. BALDWIN.
